DESIGN FOR A DRIVE SHAFT HOUSING FOR
AN OUTBOARD MOTOR

Elmer C. Kiekhaefer, Cedarburg, Wis.

Application September 5, 1947, Serial No. 141,230

Term of patent 14 years

(Cl. D71—1)

To all whom it may concern:

Be it known that I, Elmer C. Kiekhaefer, a citizen of the United States, residing at Cedarburg, in the county of Ozaukee and State of Wisconsin, have invented a new, original, and ornamental Design for a Drive Shaft Housing for an Outboard Motor, of which the following is a specification, reference being had to the accompanying drawing, forming part thereof.

In the drawing:

Fig. 1 is a side perspective view of a drive shaft housing for an outboard motor embodying my new design.

Fig. 2 is a front elevation thereof;

Fig. 3 is a rear elevation of the drive shaft housing alone; and

Fig. 4 is an underneath plan view of the drive shaft housing.

The dotted line illustrations are for purely illustrative purposes.

I claim:

The ornamental design for a drive shaft housing for an outboard motor, as shown and described.

ELMER C. KIEKHAEFER.
